Primary Examiner — Susan Bennett Hattan*(74) Attorney, Agent, or Firm* — Buchanan Ingersoll & Rooney PC**CLAIM**

The ornamental design for a Roman shade having a mesh liner, as shown and described.

DESCRIPTION

FIG. 1 is a rear view of the Roman shade having a mesh liner; and,

FIG. 2 is an enlarged view of a portion of the mesh liner circled in chain line in FIG. 1.

The bottom rail illustrated in FIG. 1 is shown in broken lines and forms no part of the claimed design. The Roman shade is shown with a symbolic break in its length, the appearance of any portion of the article between the break lines forms no part of the claimed design.
